UNITED STATES PATENT OFFICE.

EDMUND McLOUGHLIN, OF BROOKLYN, NEW YORK.

PLAQUE.

SPECIFICATION forming part of Letters Patent No. 311,772, dated February 3, 1885.

Application filed September 1, 1884. (No model.)

To all whom it may concern:

Be it known that I, EDMUND McLOUGHLIN, a citizen of the United States, and a resident of Brooklyn, Kings county, New York, have 5 invented certain Improvements in Plaques for Artistic Purposes, of which the following is a specification.

My invention relates to plaques for artistic purposes, the object being, in the main, to provide a satin surface to receive a painting.

The essential feature of the invention consists in providing a concave plaque having a body or backing of paper, metal, papier-maché, or other similar substance capable of being 15 stamped or embossed, with a satin face upon which the painting may be executed.

Another feature of the invention consists in providing a satin-faced plaque with a border or rim bearing raised or embossed ornamental figures—as, for example, a vine with leaves and flowers.

Another feature of the invention consists in providing such satin-faced plaque with a binding of cord, usually of silk, or having a silken face to correspond in luster with the satin surface.

In the drawings illustrating my invention, Figure 1 is front view of my improved plaque, and Fig. 2 is a cross section of the same.

30 In carrying out my invention, I take a piece of the material for the backing A, preferring a tough stiff paper, and upon this secure, by means of any suitable adhesive material, a piece of satin, B. This composite piece is then placed 35 in an embossing press or die and embossed. This operation imparts the necessary concavity and produces the raised flowers, figures, or other ornamentation in relief on the border a. The plaque is now trimmed and the binding-cord C attached by an adhesive material, or in 40 any other known way.

In order to make room for the cord C, I usually emboss a bead, b, in relief around the margin and near the edge of the plaque, and outside of this form a circumferential recess, c, Fig. 2, in which the cord rests.

The drawings show a circular plaque; but it may have any form—as, for example, oval, elliptical, or even rectangular.

The ornamentation in relief around the border of the plaque may be omitted, if preferred, in order to leave room for painting in an ornamental design in its place.

The binding cord may be omitted, especially if the plaque is to be framed; or some other binding may be substituted for the cord, as a binding of metal or chenille, for example.

The satin face and binding-cord may be of any color.

It will be observed that I first secure the 60 satin to a flat backing by some suitable adhesive substance, and then form the plaques by embossing the whole, including the backing fabric, so as to form a concave plaque with a raised rim.

I am aware that picture and mirror frames have been ornamented by covering their surfaces with previously-embossed velvet, plush, &c.; but this I make no claim to. My invention relates only to plaques for ornamenting, 70 formed by embossing the compound fabric previously prepared.

Having thus described my invention, I claim—

1. As an improved article of manufacture, 75 a plaque formed of a backing fabric, A, to impart strength and stiffness, and a face fabric of satin, B, secured to the backing by an adhesive material, the said compound fabric being embossed in order to impart a concave 80 form to the central portion thereof, and to form a border, a, around said central portion, substantially as shown and described.

2. As an improved article of manufacture, 85 a plaque composed of a stiff backing, A, and a satin face, B, attached to said backing by an adhesive material, the compound fabric thus formed being embossed to impart the proper concavity to its central portion, and to form a marginal border, a, on said concave 90 portion, having figures in relief thereon, substantially as shown and described.

3. As an improved article of manufacture, 95 a plaque composed of a stiff backing, A, and a satin face, B, said compound fabric being embossed to impart to it the concavity and border ornamentation, substantially as shown and described, and a binding of cord, C, around

the margin of its border, substantially as shown and described.

4. As an improved article of manufacture, an embossed satin-faced plaque provided with a bead, *b*, near its margin, a circumferential recess, *c*, exterior to said bead, and a binding-cord secured in said recess, substantially as shown and described.

In witness whereof I have hereunto signed my name in the presence of two subscribing to witnesses.

EDMUND McLOUGHLIN.
